UNITED STATES PATENT OFFICE.

EDWARD R. IVES, OF BRIDGEPORT, CONNECTICUT.

DESIGN FOR A TOY CANNON.

SPECIFICATION forming part of Design No. 25,239, dated March 10, 1896.

Application filed December 28, 1895. Serial No. 573,678. Term of patent 7 years.

To all whom it may concern:

Be it known that I, EDWARD R. IVES, a citizen of the United States, residing at Bridgeport, in the county of Fairfield and State of Connecticut, have invented and produced a new and original Design for a Toy Cannon; and I do declare the following to be a full, clear, and exact description of the same, reference being had to the accompanying drawings, forming a part thereof.

In the drawings, Figure 1 is an elevation of a toy cannon embodying my design partly in section, and Fig. 2 is a plan view.

The leading feature of my design consists of a toy cannon mounted on a wheel-carriage and having its chase or barrel ribbed or corrugated, the rear end of the barrel being separated from the breech by a cylindrical flange

and the barrel having also a second cylindrical flange near its front end. 20

1 denotes the chase or barrel, which is ribbed or corrugated, as shown; 2, the breech; 3, the carriage; 4, the axle; 5, the wheels; 6, the cylindrical flange between the barrel and breech, and 7 the cylindrical flange near the front end of the barrel. 25

Having thus described my invention, I claim—

The design for a toy cannon substantially as shown and described. 30

In testimony whereof I affix my signature in presence of two witnesses.

EDWARD R. IVES.

Witnesses:

A. M. WOOSTER,
S. V. RICHARDSON.
